UNITED STATES PATENT OFFICE.

DAVID N. CROSTHWAIT, JR., OF MARSHALLTOWN, IOWA, ASSIGNOR TO C. A. DUNHAM COMPANY, OF MARSHALLTOWN, IOWA, A CORPORATION OF IOWA.

VACUUM HEATING SYSTEM.

Application filed June 16, 1928. Serial No. 285,885.

This invention relates to a vacuum steam heating system, and more particularly to a system adapted to operate with steam at controlled sub-atmospheric pressures, as 5 disclosed in the patent to Dunham 1,644,114, granted October 4, 1927.

In a system of this type, steam is supplied under a vacuum, or at a sub-atmospheric pressure, to an evacuated condensing space 10 or radiator. A reducing valve, or generator-control mechanism, is provided for regulating the sub-atmospheric pressure of the steam in the radiator. The pressure of the steam determines its temperature, and consequently 15 the amount of heat given out by the radiator. A return main for withdrawing air and condensate from the radiator leads through a thermostatically controlled steam trap which prevents the escape of steam from the radiator. An exhausting mechanism operates on the return main to withdraw condensate and maintain the vacuum in the system. A differential pressure controller connected between the supply 20 and return sides of the system governs the operation of the exhausting means so as to maintain a substantially constant and predetermined difference in pressure between the supply and exhaust sides of the radiator 25 no matter what the absolute pressure of the steam in the radiator may be.

In heating buildings in many sections of the country, provision must be made to care for sudden and severe wind conditions. 30 For example, in certain localities there are times when high winds accompanied by falling temperatures come from the north. In such instances the north side of a building is hard to heat whereas the other sides may 35 be heated with relative ease. In order to combat this condition, it has been proposed to have separate and distinct heating systems for the different portions of a building so that steam at a higher pressure and temperature 40 can be supplied to the heating system in that portion of a building subjected to the more severe weather conditions, while lower pressure steam can be supplied to the system or systems in those portions of the 45 building where less heat is required. How-

ever, in many instances the cost resulting from the duplication or multiplication of parts makes this method of procedure prohibitive.

The general object of this invention is to 55 provide a vacuum heating system of this type involving two or more separate and distinct radiating or condensing systems for different parts of the building, all of the systems being supplied from the same source 60 of steam, and a single exhausting mechanism being utilized to maintain the requisite sub-atmospheric pressures throughout the various parts of the system.

Numerous other objects and advantages 65 of this system will be apparent from the following detailed description of certain approved forms of apparatus for carrying out the principles of this invention.

In the accompanying drawings: 70

Fig. 1 is a diagrammatic elevation showing one form of the apparatus.

Fig. 2 is a view similar to a portion of Fig. 1 showing a modification.

Fig. 3 is a vertical central section through 75 a differential pressure controlled valve.

In Fig. 1 is illustrated an example of a heating apparatus including two separate radiating systems adapted to operate simultaneously at different sub-atmospheric pressures, although it will be apparent as the description progresses that more than two such systems could be operated in the same manner. Several portions of the apparatus are common to the two heating systems, 80 principal among which are the generator A, the exhausting mechanism indicated generally at B, the flash tank C, the differential pressure controllers D and E, and numerous auxiliary connections between these several parts as hereinafter described. The generator or boiler A which may be of any approved form, furnishes steam to header 1, from which a drip pipe 2 leads back to the lower portion of the boiler at 3. A normally closed drain connection for the system is indicated at 4.

The exhausting mechanism B is substantially the same as that disclosed in the Dunham patent hereinabove referred to. A cen- 100

trifugal pump 5 driven by motor 6 withdraws water through pipe 7 from the lower portion of tank 8 and projects this water upwardly through the ejector 9 and thence through pipe 10 back into the upper portion of tank 8. A partial vacuum is created by the liquid stream within the ejector casting, and the air and condensate withdrawn from the radiating systems through pipe 11 and one-way valve 12 are entrained within the liquid stream and delivered into tank 8. The air escapes through pipe 13 and outwardly opening check valve 14. Since condensate is continually delivered to tank 8, the water level within this tank will gradually rise and when a certain level is reached the float 15, through lever and link connections 16, will open the valve 17, whereupon the pump 5 will deliver water from the tank 8 through pipe 18 and check-valve 19 into drip pipe 2 and thence back into the boiler A. When the water level within tank 8 has been sufficiently lowered, the valve 17 will be closed by the downward movement of float 15.

The starting and stopping of motor 6 is controlled by starter 20, connected through leads 21 and 22 with motor 6. The power lines running to starter 20 are indicated at 30 23 and 24. Starter 20 is connected by leads 25 and 26 with the switch 27 of the differential-pressure controller D. This controller may be the same as that disclosed in the Dunham patent above referred to, or in 35 the co-pending application of McMurrin, Serial No. 174,994, filed March 12, 1927. In general, the controller comprises a casing divided into two chambers by a flexible diaphragm. The two chambers are connected respectively with the supply and return sides of one of the heating systems by pipe connections hereinafter described. A spring tends to urge the diaphragm in one direction, the action of the spring being balanced 40 by the desired pressure differential between the supply and return sides of the system. When the pressure differential falls below the desired minimum, the spring will actuate the diaphragm and a stem projecting 45 therefrom in one direction, thereby closing the switch 27, which through starter 20 starts the operation of motor 6 and exhausting mechanism B, so as to withdraw fluids from the return side of the system and increase the pressure differential. When the 50 desired pressure differential has been attained, the diaphragm will overcome the spring and open switch 27, whereupon motor 6 and exhausting mechanism B are again 55 temporarily stopped. All of the above is substantially the same as in the Dunham patent hereinabove referred to.

Steam is delivered from the header 1 through supply mains F and F' to the two 60 separate radiating systems. The principal

elements of these systems are substantially identical and comprise a main cut-off valve G, a reducing valve H, a plurality of radiating units J, a return main K, and other auxiliary elements and connections hereinafter described. The elements of the radiating system at the right hand side of Fig. 1 are indicated by unprimed reference characters, whereas the similar elements of the radiating system at the left of Fig. 1 are indicated by similar primed reference characters. As here shown, the right hand system comprises two radiators J, whereas the left hand system discloses only a single radiator J' but it is to be understood that the 70 number of radiators in each system could be increased as found necessary or desirable. 75

The cut-off valve G is normally open when the system is in operation. The reducing valve H may be of a well known form, such as disclosed in the Dunham patent hereinabove referred to. It comprises a pair of balanced valves in the casing 28 for controlling the flow of steam at boiler pressure in the portion 29 of supply main F, into the 80 low pressure portion 30 of this supply main. The valves in casing 28 are controlled through stem 31 from a diaphragm located in casing 32, this diaphragm being subject on one side to atmospheric pressure, and on the other side 85 to the sub-atmospheric pressure existing in the portion 30 of supply main F, this pressure being delivered through supply conduit 33 which connects with supply main F at some little distance from casing 28 so as not to be 90 influenced by the fluctuations in pressure within the valve chamber. A lever 34 fulcrumed at 35 and pivoted at 36 to operating stem 31, supports from its ends the adjustable weights 37 and 38. By properly adjusting these weights, a force is exerted through lever 34 on stem 31 which either assists or opposes the pressure differential exerted on the diaphragm in casing 32. The resultant 95 force applied to stem 31 either opens or closes the valves in 28. The weights 37 and 38 are so adjusted that when the desired vacuum or sub-atmospheric pressure is attained in the portion 30 of supply main F, the diaphragm 100 in casing 32 will be moved to close the valves in 28 and shut off the flow of further steam into the supply main from header 1. As the steam in supply main F is condensed or otherwise dissipated, the pressure in the supply main will be lowered whereupon the diaphragm will be actuated in the opposite direction to open the valves in 28 and admit more steam to the supply main F. This action will be substantially continuous so that 105 the steam in portion 30 of supply main F (and consequently in radiators J as will be hereinabove apparent) can be maintained substantially constant at any sub-atmospheric pressure regardless of the pressure of the 110 115 120 125 130

steam supplied from generator A through header 1.

This sub-atmospheric pressure steam is delivered from supply main F to each radiator J through a steam riser 39 and a normally open inlet valve 40. A steam trap 41 is interposed between the lower portion of radiator J and a pipe 42 leading to return main K. When steam from radiator J enters the steam trap 41 it will expand the operating means within this trap and close the valve to prevent the escape of steam into the return main. When sufficient condensate or air has accumulated, the valve operating means will be cooled and will contract to open the valve and permit the escape of the condensate and air through pipe 42 to the return main K. The condensate which accumulates in supply main F is delivered through float and thermostatic trap 43, and pipe connections 44 and 45 into return main K. Return main K leads down through cut-off valve 46 to the pipe 11 leading to ejector 9 of the exhausting mechanism B.

An alternative pipe connection 47 branches from return main K above the cut-off valve 46, and leads through a second cut-off valve 48 into the flash tank C. It will be apparent that when valve 48 is closed and valve 46 open, condensate and air in return main K will be delivered directly to the ejector 9 of exhausting mechanism B. On the other hand, when valve 46 is closed and valve 48 is open, the condensate and air in return main K will be delivered through the alternative pipe connection 47 into the flash tank C. The flash tank C is provided for the purpose of permitting the condensate returning from the portion of the heating system that is operating at the higher pressure to re-vaporize temporarily as a result of expanding to the pressure existing in the suction to the vacuum pump, which is substantially equal to the pressure existing in that portion of the system operating at the higher vacuum or lower pressure. The condensate accumulating in flash tank C drains through pipe 49, float trap 50 and outlet 51 into one or the other of the return mains K or K', or the pipe 11, and is thence drawn into the exhausting mechanism B. The purpose of the float trap 50 is to prevent any steam entering the return main as a result of re-evaporation occurring in flash tank C.

An equalizing pipe 52 extending from the upper portion of tank C to the float trap 50 permits the ready entrance of condensate into the trap 50.

A pipe 53 leads from the upper portion of flash tank C to a three-way valve L from which branch pipes 54 and 54' lead through steam traps 55 and 55' to the respective return mains K and K'. By suitably turning the three-way valve L, the flash tank C is placed in communication through pipe 53

and branch pipe 54 or 54' with the return pipe of that system which is operating at the lower pressure or higher vacuum. The thermostatic traps 55 and 55' are provided to prevent the passage of any steam which might form as a result of re-evaporation in flash tank C into the return mains. 70

The differential pressure controlled valve E (shown in detail in Fig. 3) automatically opens and closes the suction pipe 53. A 75 pair of connected balanced valves 56 close valve openings in the web 57 within valve casing 58 to govern the passage of fluid through the valve. The diaphragm yoke 59 is secured by set screw 60 upon an upper extension 61 of valve casing 58. The valve stem 62 extends upwardly from valves 56 through stuffing box 63 and is threaded into the lower end of yoke 64 being secured in place by lock nut 65. A lever 66 carrying an adjustable weight 67 extends through yoke 64 and is fulcrumed at one end 68 in the diaphragm yoke 59. A main diaphragm 69 is clamped at its periphery between the two similar annular dished casing members 90 70 and 71. The lower casing member 70 is secured to the upper flared end 72 of yoke 59 by means of a plurality of bolts 73, a smaller flexible diaphragm 74 being clamped between the members 70 and 72. A third 95 diaphragm 75, similar to the small diaphragm 74, is secured against the upper side of casing member 71 by a cover member 76 secured in place by bolts 77. Cover 76 is provided with apertures 78 whereby air at 100 atmospheric pressure is admitted to the chamber above the upper diaphragm 75. A pair of diaphragm plates 79, one at either side of the main diaphragm 69, and the spacers 80 and 81 mounted between the diaphragms, are all carried around a stem 82 which projects through central apertures in the three diaphragms. The three diaphragms 74, 69 and 75 are secured together to operate as a unit by the washers 83 and nuts 84 on 105 the respective ends of stem 82, these parts also serve to seal the central apertures in the diaphragms. A stem 85 is threaded into the upper end of yoke 64 and secured in place by lock nut 86, the upper end of stem 110 85 being secured to the lower end of stem 82 by collar 87. The stops 88 and 89 formed within the casing members 70 and 71 limit the movement of diaphragm 69 in either direction. A pipe 90 is threaded into lower 115 casing member 70 at 91 so as to communicate with the chamber between diaphragms 74 and 69 and a pipe 92 threaded into casing member 71 at 93 communicates with the chamber between diaphragms 69 and 75. 120

The pipes 90 and 92 are adapted to communicate with relatively high and low pressure spaces between which the desired pressure differential is to be maintained. The smaller diaphragms 74 and 75 are each sub- 125

130

ject on their outer face to atmospheric pressure, so that these diaphragms will constantly balance one another. Their purpose is to avoid the necessity for stuffing boxes about the vertically movable valve stem 82. It will be noted that the weight 67 constantly tends to open the valves 56, but this weight is opposed by the higher pressure existing in the chamber beneath diaphragm 69 which tends to lift the diaphragm and hence raise the valves 56 to their closed positions. In other words, the pressure differential acting on diaphragm 69 tends to keep the valves 56 closed, and this force is opposed by the weight 67 which tends to open the valve. By properly adjusting the weight 67, when the pressure differential falls below the desired minimum the weight 67 will overcome the pressure acting on diaphragm 69 and open the valves. When the pressure differential has again been built up to the desired maximum, this pressure will overcome the weight 67 and lift same so as to close the valves 56.

25 The pressure control pipes 90 and 92 lead respectively to the two similar four-way valves M and N. These valves M and N may be designated respectively the high and low pressure four-way valves, although these terms are merely relative since the pressures of the fluids passing through each valve are normally sub-atmospheric.

An equalizing pipe 94 (in each radiating system) connects the return main K with the supply main F, this pipe including a one-way valve 95 opening toward the supply main F, and a normally open cut-off valve 96. The check valve 95 will normally be held closed by the higher pressure in supply main F, but will open if for any reason the pressure in the supply main should fall below the pressure in the return main so as to equalize the pressures in the two pipes. Surge chambers 97 and 98 are conveniently located in the high and low pressure portions of equalizing pipe 94, and pressure control pipes 99 and 100 extend respectively from these surge chambers to the high and low pressure valves M and N. The surge chambers serve to maintain the proper head of water, compensating for the volume displaced by the movements of the diaphragms in the differential pressure control devices. Pressure control pipes 101 and 102 connect the respective high and low pressure sides of differential controller D with the high and low pressure four-way valves M and N.

Assuming first that the apparatus is to be operated so that the radiating system at the right of Fig. 1 (designated by the unprimed reference characters) is operated at the lower pressure or higher vacuum, the four-way valves M and N will be so adjusted that the control pipes 99 and 100 are respectively placed in communication with the

70 pipes 101 and 102 leading to differential pressure controller D, so that the exhausting mechanism B is directly controlled by the pressure differential existing in this lower pressure system. This same adjustment of the valves M and N will place the control pipes 99' and 100' of the other radiating system in communication respectively with the pipes 90 and 92 leading to the differential pressure controller E. The 75 three-way valve L will be so adjusted that pipe 53 is in communication with branch pipe 54 leading to the return main K of the lower pressure system. Cut-off valve 46 will be opened and cut-off valve 48 closed 80 so that return main K communicates directly with the exhausting mechanism B. At the same time, cut-off valve 46' will be closed and cut-off valve 48' opened, so that the other return main K' communicates only 85 with the flash tank C.

The lower pressure or higher vacuum system at the right will now operate exactly the same as the usual differential pressure vacuum system as disclosed in the Dunham 90 patent hereinabove referred to. The sub-atmospheric pressure of the steam in the radiators J is determined by the adjustment of the reducing valve H, and the exhausting mechanism B will operate intermittently to maintain the desired vacuum in the system and also to maintain the necessary pressure differential between the supply and return sides of the system. The air and condensate are drawn directly through 100 return main K into the exhausting mechanism B, the air being discharged through vent 13 and the condensate returned at intervals to the boiler A through pipe 18.

In the other system (designated by the 105 primed reference characters) less vacuum is required since this system is to be operated with steam at a higher pressure since more heat is to be radiated. Accordingly, the reducing valve H' will be so regulated 110 that supply main F' will supply steam to the radiators J' at a higher sub-atmospheric pressure. However, it is desirable that a substantially constant pressure differential be maintained between the supply main F' 115 and the return main K', as in the radiating system first described. The differential pressure controller E is now responsive to this pressure differential between the supply main F' and return main K'. The return 120 main K' now discharges into the flash tank C so that the pressure in tank C determines the pressure in the return side of this system. The pipe connections 53 and 54 extending to the lower pressure return pipe K 125 affords a means for exhausting the tank C at intervals so as to maintain the desired degree of vacuum in the relatively higher pressure system. When the pressure differential in this system falls below the desired 130

minimum, the pressure controlled valve E will automatically open so that flash tank C is placed in communication through pipes 53 and 54 with the lower pressure return line K, thus lowering the pressure in flash tank C and in return main K'. When the necessary pressure differential has again been established in this system, valve E will automatically close. The condensate delivered into tank C is drawn out through float trap 50 and delivered through exhausting mechanism B into tank 8. The gases from tank C are exhausted through pipes 53 and 54 into return main K and thence drawn out and vented by the exhausting mechanism B.

In an exactly similar manner, when the left-hand radiating system is to be operated at the lower pressure or higher vacuum, the valves L, M and N are all reversed so that the differential controller D is operated from the left-hand system through control pipe connections 99', 101, and 100', 102. At the same time the differential pressure controlled valve E will be operated by the control pipes 99, 90, and 100, 92. The cut-off valve 46 will be closed and the valve 48 opened so that return main K will discharge into flash tank C. At the same time cut-off valve 48' will be closed and valve 46' opened so that the return line K' of the left-hand system will be directly connected with the exhausting mechanism B. The vacuum in tank C is now supplied through suction pipe line 53, 54' running to return line K' which now has the higher vacuum.

If it be desired to operate both systems at the same vacuum, then valves 48 and 48' may be closed and valves 46 and 46' opened so that both return lines K and K' discharge directly into the exhausting mechanism B. Valves M and N may be so adjusted that either of the radiating systems controls the differential pressure controller D which governs the action of pump motor 6.

A somewhat modified form of the apparatus is disclosed in Fig. 2. In this apparatus, each radiating system is provided with a differential pressure controller D, D', and the control piping is somewhat simplified. Fig. 2 discloses a portion of the apparatus shown in Fig. 1, and it is to be understood that all parts not here shown or not specifically referred to, are the same as already described in connection with Fig. 1. The pressure control pipes 99 and 100 lead from surge chambers 97 and 98 directly to the high and low pressure sides of the differential controller D. In an exactly similar manner, the pressure control pipes 99' and 100' of the other radiating system lead to the respective sides of a second differential controller D'. Branch pipes 103 and 103' lead from the pipes 99 and 99' to a rela-

tively high pressure three-way valve R, and in a similar manner branch pipes 104 and 104' lead from pipes 100 and 100' to a relatively low pressure three-way valve S. The valves R and S replace the four-way valves 70 M and N shown in Fig. 1. It will be apparent that each system is constantly connected with its respective differential controller D or D', and that either system may alternatively be connected with the differential controller E by suitably adjusting the three-way valves R and S. The leads 25 and 26 from the starter 20 of motor 6 extend to a double-throw switch 105 from which branch leads 106 and 107 to the switch 80 27 of controller D, and leads 106' and 107' extending to the switch 27' of controller D'. By throwing switch 105 to one side or the other, either controller D or D' may be placed in control of motor 6, and the other controller thrown temporarily out of service. Assuming that switch 105 is thrown to the right so that differential pressure controller D governs the motor 6, the valves R and S will be so adjusted that the differentially 90 controlled valve E is connected with the left-hand system through pipe connections 103', 90 and 104', 92. At such a time, the right-hand system will be operating at the higher vacuum and the left-hand system at 95 the higher pressure, as in the system first described. It should be noted that in order to facilitate the disclosure in the diagrammatic views and show all of the piping system, many of the pipes are shown at different elevations from those actually occupied. As a matter of fact, a great many of the pipes are grouped at the same level and would appear one behind the other if so 100 illustrated.

I claim:

1. In steam heating apparatus, a source of steam, two separate radiating systems, means for supplying steam from the source to each of these systems, and means including a single exhausting mechanism for simultaneously maintaining a different sub-atmospheric pressure in each of these systems.

2. In steam heating apparatus, a source of steam, two separate radiating systems, means for supplying steam from the source to each of these systems, and means for maintaining a different degree of vacuum in each of the systems, including a single 110 exhausting mechanism directly connected with one of the systems, and intermittently effective means interposed between the exhausting means and the other system whereby a lesser degree of vacuum is maintained 120 in the latter system.

3. In steam heating apparatus, a source of steam, two separate radiating systems, means for supplying steam from the source at reduced pressure to each system, the 130

pressure in one system being maintained lower than the pressure in the other system, a single exhausting mechanism for withdrawing air and condensate from both systems, the exhausting mechanism being in direct connection with the system operating at the lower pressure, a flash tank into which the other system discharges, means for discharging condensate from the flash tanks to the exhausting mechanism, a suction pipe connecting a portion of the lower pressure system with the flash tank, and an intermittently operated valve in this pipe.

4. In steam heating apparatus, a source of steam, two separate radiating systems, means for supplying steam from the source at reduced pressure to each system, the pressure in one system being maintained lower than the pressure in the other system, a single exhausting mechanism for withdrawing air and condensate from both systems, the exhausting mechanism being in direct connection with the system operating at the lower pressure, a flash tank into which the other system discharges, means for discharging condensate from the flash tank to the exhausting mechanism, a suction pipe connecting a portion of the lower pressure system with the flash tank, and a pressure controlled valve in this pipe.

5. In steam heating apparatus, a source of steam, two separate radiating systems, means including supply mains and return mains for maintaining steam from the source in each of these systems, a reducing valve in each supply main whereby the steam is simultaneously maintained at a different sub-atmospheric pressure in each system, an exhausting mechanism, and connections between the exhausting mechanism and the return mains for maintaining a predetermined pressure differential between the supply and return sides of each radiating system.

45 6. In steam heating apparatus, a source of steam, two separate radiating systems, means including supply mains and return mains for maintaining steam from the source in each of these systems, a reducing valve in each supply main whereby the steam is simultaneously maintained at a different sub-atmospheric pressure in each system, an exhausting mechanism, a motor for operating the exhausting mechanism, a differential pressure controller for the motor connected between the supply and return sides of the system operating at the lower pressure, an exhaust conduit between the return main of this system and the return main of the system operating at the higher sub-atmospheric pressure, a valve in this conduit and a differential controller for this valve connected between the supply and return sides of the higher pressure system.

65 7. In steam heating apparatus, a source of

steam, two separate radiating systems, means including supply mains and return mains for maintaining steam from the source in each of these systems, a reducing valve in each supply main whereby the steam is simultaneously maintained at a different sub-atmospheric pressure in each system, an exhausting mechanism, a motor for operating the exhausting mechanism, a differential pressure controller for the motor connected between the supply and return sides of the system operating at the lower pressure, a flash tank, the return main of the lower pressure system leading to the exhausting mechanism and the return main of the higher pressure system leading to the flash tank, a pipe connecting the lower pressure return main with the flash tank, a valve in this pipe, and a differential pressure controller for this valve connected between the supply and return sides of the higher pressure system.

8. In steam heating apparatus, a source of steam, two separate radiating systems, means including supply mains and return mains for maintaining steam from the source in each of these systems, a reducing valve in each supply main whereby the steam is simultaneously maintained at a different sub-atmospheric pressure in each system, an exhausting mechanism, a motor for operating the exhausting mechanism, a differential pressure controller for the motor connected between the supply and return sides of the system operating at the lower pressure, a flash tank, exhaust pipe connections between the exhausting mechanism and the return main of the lower pressure system and the flash tank, a valve in the exhaust pipe leading to the flash tank, the return main of the higher pressure system also leading to the flash tank, and a differential controller for the last mentioned valve connected between the supply and return sides of the higher pressure system.

9. In steam heating apparatus, a source of steam, a heating system comprising a radiator, a supply main, a return main, and a flash tank into which the return main discharges, a second heating system, an exhausting mechanism, means controlling the exhausting mechanism whereby it maintains a lower pressure in the second heating system than the pressure desired in the flash tank, a pipe connection between the flash tank and the second heating system, a valve in this pipe, a differential pressure controller for operating the valve, and control pipe connections from the controller to the supply and return sides of the radiator.

10. In steam heating apparatus, a source of steam, a heating system comprising a radiator, a supply main, a return main, and a flash tank into which the return main discharges, an exhausting mechanism, a second

heating system, means controlling the exhausting mechanism whereby it maintains a lower pressure in the second heating system than the pressure desired in the flash-tank, a pipe connection between the flash tank and the second heating system, a valve in this pipe, a differential pressure controller for operating the valve, control pipe connections from the controller to the supply and return sides of the radiator, and a float-valve for discharging condensate from the flash tank.

11. In steam heating apparatus, a source of steam, a heating system comprising a radiator, a supply main, a return main, and a flash tank into which the return main discharges, a second heating system, means for maintaining a lower pressure in the second heating system than that desired in the flash tank, a pipe connection between the flash tank and the second heating system, a valve in this pipe, and a differential pressure controller connected with the supply and return sides of the radiator for operating this valve.

12. In steam heating apparatus, a source of steam, a radiator, a supply main, a return main, a flash tank into which the return main discharges, a second radiating system including a return main, means for maintaining a lower pressure in this second return main than that desired in the first return main, a pipe connection between the second return main and the flash tank, a valve in this pipe, and a differential pressure controller connected with the supply and return sides of the radiator for operating the valve.

13. In steam heating apparatus, a source of steam, a heating system comprising a supply main leading from the source, a reducing valve for controlling the pressure in the supply main, a return main, a radiator in open communication with the supply main, connections including a thermostatic trap from the radiator to the return main, and a flash tank into which the return main discharges, a second heating system, an exhausting mechanism, means controlling the exhausting mechanism whereby it constantly maintains a lower pressure in the second heating system than that required in the flash tank, a pipe connecting the flash tank with the second heating system, a valve in this pipe, and a differential pressure controller connected with the supply and return mains and operating the valve.

14. In a steam heating system, a generator, a header leading therefrom, two separate radiating systems each including a supply main leading from the header, a reducing valve in the supply main, a radiator in open communication with the supply main, a return main, discharge connections including a thermostatic trap between the radiator and the return main, and pressure control pipes leading from the supply and return sides of the

system; an exhausting mechanism adapted to withdraw gases and condensate from the two systems and return the condensate to the generator, a flash tank, valved connections whereby the return mains may be alternatively connected to discharge either into the flash tank or direct into the exhausting mechanism, valved pipe connections leading from the flash tank for alternatively placing same in communication with either return main, a cut-off valve in this pipe connection, a differential pressure controller for operating the valve, a second differential pressure controller for governing the operation of the exhausting mechanism, and valved pipe connections for alternatively placing the pressure control pipes leading from either radiating system in communication with the respective differential pressure controllers.

15. In a steam heating system, a generator, a header leading therefrom, two separate radiating systems each including a supply main leading from the header, a reducing valve in the supply main, a radiator in open communication with the supply main, a return main, discharge connections including a thermostatic trap between the radiator and the return main, and pressure control pipes leading from the supply and return sides of the system; an exhausting mechanism adapted to withdraw gases and condensate from the two systems and return the condensate to the generator, a flash tank, an outlet for condensate leading from the flash tank to the exhausting mechanism said outlet including a float-trap, valved connections whereby the return main may be alternatively connected to discharge either into the flash tank or direct into the exhausting mechanism, valved pipe connections leading from the flash tank for alternatively placing same in communication with either return main, a cut-off valve in this pipe connection, a differential pressure controller for operating the valve, a second differential pressure controller for governing the operation of the exhausting mechanism, and valved pipe connections for alternatively placing the pressure control pipes leading from either radiating system in communication with the respective differential pressure controllers.

16. In a steam heating system, a generator, a header leading therefrom, two separate radiating systems each including a supply main leading from the header, a reducing valve in the supply main, a radiator in open communication with the supply main, a return main, discharge connections including a thermostatic trap between the radiator and the return main, and pressure control pipes leading from the supply and return sides of the system; an exhausting mechanism adapted to withdraw gases and condensate from the two systems and return the condensate to the generator, one of

the return mains discharging directly into the exhausting mechanism, a flash tank into which the other return main discharges, a pipe connecting the flash tank with the first return main, a valve in this pipe, a differential pressure controller for operating the valve, a second differential pressure controller for governing the operation of the exhausting mechanism, the pressure control pipes from the system which discharges into the flash tank leading to the first mentioned differential controller, and the pressure control pipes from the other system leading to the second controller.

17. In a steam heating system, a generator, a header leading therefrom, two separate radiating systems each including a supply main leading from the header, a reducing valve in the supply main, a radiator in open communication with the supply main, a return main, discharge connections including a thermostatic trap between the radiator and the return main, and pressure control pipes leading from the supply and return sides of the system; an exhausting mechanism adapted to withdraw gases and condensate from the two systems and return the condensate to the generator, one of the return mains discharging directly into the exhausting mechanism, a flash tank into which the other return main discharges, an outlet for condensate leading from the flash tank to the exhausting mechanism said outlet including a float-trap, a pipe connecting the flash tank with the first return main, a valve in this pipe, a differential pressure controller for operating the valve, a second differential pressure controller for governing the operation of the exhausting mechanism, the pressure control pipes from the system which discharges into the flash tank leading to the first mentioned differential controller, and the pressure control pipes from the other system leading to the second controller.

18. In a steam heating system, a source of steam, two separate radiating systems, means including supply and return mains for furnishing steam from the source to each of these systems, a reducing valve in each supply main whereby the steam is simultaneously maintained at a different sub-atmospheric pressure in each system, a pair of four-way valves, pressure-control pipes extending from the supply and return sides of each radiating system, the two supply pressure pipes extending to one of the valves and the two return pressure pipes extending to the other valve, an exhausting mechanism, a motor for operating the exhausting mechanism, a flash tank, the return pipes from the two systems each having alternative connections with the exhausting mechanism and the flash tank, valves for controlling these connections, a differential

pressure controller for the motor, a pipe connecting the high pressure side of this controller with one of the four-way valves, a pipe connecting the low pressure side of the controller with the other four-way valve, a three-way valve, pipes leading from this valve to each of the return mains, a pipe leading from the three-way valve to the flash tank, a valve in this latter pipe, a differential pressure controller for operating this valve, and pipes leading from the high and low pressure sides of this controller to the remaining ports of the respective four-way valves.
